UNITED STATES PATENT OFFICE.

JACOB S. NISWANDER, OF OAKLAND, CALIFORNIA.

FISHING-ROD.

SPECIFICATION forming part of Letters Patent No. 230,650, dated August 3, 1880.

Application filed April 1, 1880. (No model.)

To all whom it may concern:

Be it known that I, JACOB S. NISWANDER, of Oakland, Alameda county, in the State of California, have invented an Improved Fishing-Rod; and I do hereby declare that the following is a full, clear, and exact description thereof, reference being had to the accompanying drawings.

This invention contemplates improvements in fishing-rods; and it consists of a rod made in sections of tempered steel, with the said sections formed with longitudinal ribs extending along a central solid core, substantially as hereinafter more fully set forth.

Referring to the drawings, Figure 1 is a perspective view. Fig. 2 is an enlarged detail view of the ends of two adjoining sections.

A B C D represent the joints or sections of a jointed fishing-rod. These joints or sections I make of steel-rod, which is drawn out to the required size and taper, and properly tempered, so that when they are connected together, in the usual way, they will form a strong, light, and flexible rod, which tapers from its handle to its outer end.

The steel rods or joints are made with a series of longitudinal ribs, *i i*, radiating from a central core, *i'*. The section or joint at the handle end of the rod I usually make hollow.

The best form of ribbed joint will be triangular in cross-section, the faces of which can be made concave, so as to leave a rib at each corner or angle; but it can be made with a larger number of faces and ribs, if desired.

By making the joints with longitudinal ribs I obtain a very light rod, which will have greater strength than a round rod containing an equal amount of metal.

A fishing-rod thus constructed of steel is much lighter and stronger, and possesses

greater flexibility than the bamboo rods ordinarily used. When properly tempered they will not rust easily if proper care is taken of them, or a coat of varnish could be put over them to protect them from moisture.

45

To unite the joints or sections together I employ a metallic coupling-joint, *c*, the ends of which are bored out and tapped with screw-threads. The ends of the joints or sections of the fishing-rod are also tapped with screw- 50 threads, so that they can be screwed into the ends of the coupling-joint, thus forming a strong and positive connection that cannot become detached by ordinary work.

The eyes *f f*, for holding the fishing-line, are 55 attached to the coupling-joints, either directly or by means of bands passing around the joints, as shown at Fig. 1. I shall ordinarily provide a short wooden handle, *g*, covering a portion of the largest or handle joint, to which the reel 60 is attached. This forms a complete fishing-rod, which possesses all the peculiar qualities so essential in such rods, in order to give the fisherman confidence in operating with it. It can be taken apart and packed in a small compass, so as to be convenient to carry, and it can be quickly put together again.

Having thus described my invention, what I claim, and desire to secure by Letters Patent, is—

70

A jointed fishing-rod the sections of which consist of tempered steel having a central core and longitudinal ribs, substantially as and for the purpose set forth.

In witness whereof I have hereunto set 75 my hand and seal.

J. S. NISWANDER. [L. S.]
